UNITED STATES PATENT OFFICE.

ADAM CRAIGON, OF TORONTO, ONTARIO, CANADA.

INTERNAL-COMBUSTION ENGINE.

Application filed July 2, 1926. Serial No. 120,135.

This invention relates to double acting internal combustion engines, and particularly to that type in which scavenging air is employed to clear the products of combustion from the cylinders, and my object is to devise an engine of this type in which a substantial increase of power may be obtained per unit of weight, which will be simple and compact, which requires no 5 stuffing boxes and in which the parts are readily accessible for inspection and repair.

I attain my object by means of a construction which may be briefly described as follows. Within a cylinder is fitted a stationary piston supported from a stationary part beyond the range of motion of the trunk piston. One combustion chamber is thus formed between the outer end of the trunk piston and the end of the cylinder and a 10 second combustion chamber between the inside of the head of the trunk piston and the stationary piston.

The sleeve or trunk of the trunk piston serves to control ports for the admission and 15 exhaust of air and the exhaust of the products of combustion. I, preferably, arrange the cylinders in pairs side by side so that the trunk pistons may be connected in pairs to a crosshead, a connecting rod connecting 20 the cross head with a crank of the engine crank shaft.

The invention is hereinafter described and illustrated in the accompanying drawings in which

35 Fig. 1 is a vertical transverse section of an engine constructed in accordance with my invention;

Fig. 2 a similar view taken at right angles to Fig. 1;

40 Fig. 3 a similar view showing two cylinders arranged side by side;

Fig. 4 a similar view showing a different arrangement of air ports.

In the drawings like numerals of reference indicate corresponding parts in the different figures.

Referring particularly to Figs. 1 and 2, 1 is a cylinder provided with the usual water jacket. In this cylinder is longitudinally 50 movable a trunk piston 2, the sleeve 3 of this piston being pivotally connected with the upper ends of the connecting rods 4, the other ends of which are connected with the cranks 5 of the engine shaft 6.

55 Within the sleeve of the trunk piston is located a fixed piston 7, which is shown as

provided with a sleeve 8 formed with a flange 9 bolted to the base casting 10 by means of the bolts 11. This stationary piston is preferably water cooled as shown. 60 With this arrangement a combustion chamber 12 is formed between the trunk piston and the end of the cylinder 1 and the second combustion chamber 12^a between the inner side of the head of the trunk piston and the stationary piston 7. Each chamber is provided with a fuel injection valve 13 of any known type.

At one side of the cylinder is located an air manifold 14 and at the other side an 70 exhaust manifold 15. Ports 16 and 17 form a communication between the air manifold and the interior of the cylinder and ports 18 and 19 form a communication between the exhaust manifold and the interior of the 75 cylinder.

The operation of the engine as described is as follows. Assuming the parts to be in the position shown in Fig. 1, scavenging air from the air manifold flows through the 80 port 16 and is shot upward by the curved deflector 20 formed on the head of the trunk piston. The air is deflected downwardly by the head of the cylinder and passes out to the exhaust manifold through the ports 18. 85 Products of combustion of the previous explosion stroke of the engine are thus swept out and the cylinder filled with fresh air. As in other engines of this type, means must be provided for the supplying of air under 90 pressure to the air manifold, but as these arrangements form no part of the present invention, such parts are neither shown nor described.

The trunk piston now moves upward closing the ports 16 and 18 and compressing the air in the combustion chamber 12. As usual in engines of this type, compression is carried to such a point that the temperature of the air is raised sufficiently to ignite the fuel injected through the upper fuel injecting valve 13. The fuel is ignited and forces down the trunk piston back to the position shown in Fig. 1. The upward stroke of the trunk piston has been caused by the combustion of 95 the fuel in the combustion chamber 12^a. When the trunk piston is at the upper end of its stroke a port 27 in the side of the sleeve 8 is brought into alignment with the air inlet port 17, and a port 22 in the other side 100 of the sleeve into alignment with the exhaust port 19. A flow of scavenging air will 105 110

then pass through the combustion chamber 12^a, its circulation being assisted by the deflector 23 formed on the stationary piston.

The arrangements for lubrication and for timing the fuel injection form no part of the present invention and are neither described nor shown.

In Fig. 3 I show an arrangement in which two cylinders with the other associated parts 10 are arranged side by side so that two pistons may operate on a single connecting rod and so that scavenging may occur seriatim through two combustion chambers. In this arrangement the sleeves of the trunk pistons 15 are secured to a cross head 24 to which the connecting rod 4 is pivoted. Between the two chambers at their outer ends is formed a passage 25. With this passage 25 communicates a fuel injecting valve 13. A similar 20 passage 26 is formed between the two cylinders at the other end and communicating therewith at or about the level of the upper end of the stationary piston 7. The exhaust ports 18 and 19 have a single port 18^a substituted therefor.

The mode of operation is substantially the same in this construction as in that shown in Figs. 1 and 2 with the exception that the air 30 after passing through the interior of the first combustion chamber passes through the passage 26 into the next combustion chamber, through this combustion chamber and thence to the exhaust. When the trunk pistons are up as shown in Fig. 3, the air passes 35 out of the lower combustion chamber of the first piston, through the port 27 and after passing through the passage 26, passes through the port 28 into the second combustion chamber, thence passing out through the port 22 to the exhaust. When the trunk pistons are down, the air passes into the first combustion chamber through the upper inlet port 16, through the upper combustion chamber of the first cylinder to its upper 40 end, through the passage 25, through the upper combustion chamber of the second cylinder and thence to the exhaust.

The stationary pistons are shown as secured to cylindrical supports 31 which are 50 secured to the base 10 and which serve as cross head guides.

In Fig. 4 a further modification of the air ports is shown. In this modification a false head 33 is provided serving as an 55 equivalent for the outer end of the cylinder shown in Figs. 1 and 2, this false head being secured to the head 34 of an upward extension 35 of the cylinder 1. This false head may be constructed similarly to the 60 stationary piston 7, being secured to a post 36 secured to the head 34. An upward extension 37 of the sleeve 3 is also provided which extends up into the cylinder extension 35, but is preferably separated therefrom 65 by an annular space which communicates

with the interior of the cylinder extension through the ports 38.

A piston 39 is secured to the upper end of the sleeve extension 37. This piston, reciprocating with the sleeve, provides 70 means for pumping air for use in starting or for any other purposes for which air or other fluid is used in engines of the Diesel type.

In Fig. 4 I show only one cylinder and the 75 other co-related parts, though in practice a second cylinder with co-related parts will be arranged side by side with that shown, the arrangement being in general similar to that shown in Fig. 3.

40 is a chamber communicating with the cylinder 1 below the false head 33 and which in practice will, of course, also communicate with the corresponding cylinder at the other side. Two other passageways 41 and 42 are 80 also provided communicating with the interior of the cylinder 1 and the cylinder at the opposite side (not shown). The sleeve 3 is provided with the ports 43, 44, 45, 46 and 47. The passage 41 corresponds to the passage 26 of Fig. 3 and supplies air to the combustion chambers. So also does the passage 42. When the parts are in the position shown in Fig. 4, air is passing from the 85 passage 42 through the ports 43, through the lower combustion chamber, and out through the ports 44 to the exhaust.

The passages 40 and 42 are each provided with a fuel injection valve 13. The passage 40 is shown in Fig. 4 in communication with the upper combustion chamber 12 through the port 45 as at the beginning of the firing stroke. When the trunk piston arrives at the lower end of this firing stroke the port 45 is in alinement with the air passage 41 and the port 46 is in alinement with the exhaust port 18^a and scavenging air passes through the combustion chamber.

The port 47 is now in communication with the passage 42 so that when fuel is injected 110 through the fuel injection valve 13 into the passage 42 the hot products of combustion freely pass into the combustion chamber 12^a.

In Fig. 1, I show a combined air and relief valve 48 communicating with the upper combustion chamber 12 and a relief valve 49 communicating with the lower combustion chamber 12^a. These are of known type and will be operated in a known manner.

What I claim is:

1. In an internal combustion engine of the Diesel type, the combination of two cylinders arranged side by side; a trunk piston fitted in each cylinder; a stationary piston fitted in the sleeve of each trunk piston, whereby two combustion chambers are formed, one between the trunk piston and the end of the cylinder and one between the inside of the head of the trunk piston and the stationary piston; a passage connecting 125

- the outer ends of the cylinders; a passage connecting the cylinders in substantial alinement with the upper ends of the stationary pistons; an inlet port in one cylinder and an exhaust port in the other cylinder in substantial alinement with the last mentioned passage adapted to be controlled by the sleeves of the trunk piston; ports in the trunks of the pistons adapted to form a communication between the interiors of said trunks and the last mentioned passage when the inlet and exhaust ports are open to said interiors; and means associated with each of the passages aforesaid for injecting fuel.
5. 2. In an internal combustion engine of the Diesel type, the combination of two cylinders arranged side by side; a trunk piston fitted in each cylinder; a stationary piston fitted in the sleeve of each trunk piston, whereby two combustion chambers are formed, one between the trunk piston and the end of the cylinder and one between the inside of the head of the trunk piston and the stationary piston; a passage connecting the outer ends of the cylinders; a passage connecting the cylinders in substantial alinement with the upper ends of the stationary pistons; an inlet port in one cylinder and an exhaust port in the other cylinder in substantial alinement with the last mentioned passage adapted to be controlled by the sleeves of the trunk piston and having their lower edges in substantial alinement with the upper end of the stationary piston; and ports in the trunks of the pistons adapted to form a communication between the interiors of said trunks and the last mentioned passage when the inlet and exhaust ports are open to said interiors.
4. In an internal combustion engine of the Diesel type, the combination of two cylinders arranged side by side; a trunk piston fitted in each cylinder; a stationary piston fitted in the sleeve of each trunk piston, whereby two combustion chambers are formed, one between the trunk piston and the end of the cylinder and one between the inside of the head of the trunk piston and the stationary piston; a passage connecting the outer ends of the cylinders; a passage connecting the cylinders in substantial alinement with the upper ends of the stationary pistons; an inlet port in one cylinder and an exhaust port in the other cylinder in substantial alinement with the last mentioned passage adapted to be controlled by the sleeves of the trunk piston, the inlet and exhaust ports being of a length greater than the thickness of the trunk piston; and ports in the trunks of the pistons adapted to form a communication between the interiors of said trunks and the last mentioned passage when the inlet and exhaust ports are open to said interiors.
5. In an internal combustion engine of the Diesel type, the combination of two cylinders arranged side by side; a trunk piston fitted in each cylinder; a stationary piston fitted in the sleeve of each trunk piston, whereby two combustion chambers are formed, one between the trunk piston and the end of the cylinder and one between the inside of the head of the trunk piston and the stationary piston; ports and passages in the cylinder walls and ports in the trunk pistons whereby scavenging air may be caused to flow seriatim through either pair of combustion chambers according to the position of the trunk pistons.
